UNITED STATES PATENT OFFICE

142,439

DESIGN FOR A LIGHT METER

Elwood J. Nicholson, Los Angeles, Calif., assignor
to Photo Research Corporation, San Fernando,
Calif., a corporation of California

Application May 7, 1945, Serial No. 119,441

Term of patent 14 years

(Cl. D26—5)

To all whom it may concern:

Be it known that I, Elwood J. Nicholson, a citizen of the United States, residing at Los Angeles, in the county of Los Angeles, State of California, have invented a new, original, and ornamental Design for a Light Meter, of which the following is a specification, reference being had to the accompanying drawing, forming part thereof.

Fig. 1 is a front elevational view of the light meter showing my new design.

Fig. 2 is a side elevational view.

Fig. 3 is a top view.

Fig. 4 is a bottom view.

I claim:

The ornamental design for a light meter, substantially as shown.

ELWOOD J. NICHOLSON.
